Primary Examiner — Vy N Koenig(74) Attorney, Agent, or Firm — William B. Lacy(57) CLAIM

The ornamental design for a golf ball package, as shown and described.

DESCRIPTION

FIG. 1 a top perspective view of a golf ball packaging showing our new design;

FIG. 2 is a left side view thereof, the right side view being identical to the left side view;

FIG. 3 is a top plan view thereof; and,

FIG. 4 is a front side view thereof, the back side view being identical to the front side view.

The broken lines in the drawings depict text and portions of the golf ball package that form no part of the claimed design. The black areas shown in FIGS. 1-4 depict a contrast in appearance.
